UNITED STATES PATENT OFFICE.

WILLIAM A. TOOHER, OF ST. LOUIS, MISSOURI.

HEATING FURNACE.

Application filed July 2, 1924. Serial No. 723,681.

To all whom it may concern:

Be it known that I, WILLIAM A. TOOHER, a citizen of the United States of America, a resident of the city of St. Louis, in the 5 State of Missouri, have invented certain new and useful Improvements in Heating Furnaces, of which the following is a full, clear, and exact description, reference being had to the accompanying drawings, forming 10 a part of this specification.

This invention relates generally to heating furnaces, and particularly to a simple and inexpensive casing for a heating furnace which is provided with an inner lining 15 member spaced apart from the outer wall of said casing in a manner to provide an annular air space which surrounds the heat-producing medium of said furnace. The air space mentioned is for the purpose of 20 resisting the chill of the exterior and to reduce the volume of heat dissipated through the medium of radiation.

It has been found in practice that the best 25 results are obtained when the furnace casings forming parts of certain makes of furnaces are provided with air spaces which are approximately one inch in width. Prior to this invention it was found that it was a rather difficult matter to maintain 30 a uniform space all around the furnace for the reason that the lining members which formed the inner walls of said air spaces were capable of movement relative to the outer walls of the furnace. Hence it quite 35 frequently happened that the air space of a furnace would be approximately one-half inch in width at one side of the furnace and an inch and a half at the other side of said furnace.

40 The main object of the present invention is to eliminate the difficulties suggested above, and I have therefore devised a very simple and inexpensive casing structure which is so arranged that the walls which 45 form the air spaces mentioned are in fixed relation to each other whereby a uniform air space is maintained at all times.

Another object of the present invention 50 is to provide a heating furnace of the class described with a baffle member which is interposed between the heat-producing element of the furnace and the air space thereof, said baffle member being intended to provide additional means for reducing the volume 55 of heat dissipated through the means of radiation.

With the foregoing and other objects in view, the invention comprises the novel construction, combination and arrangement of parts hereinafter more specifically described 60 and illustrated in the accompanying drawings, wherein is shown the preferred embodiment of the invention. However, it is to be understood that the invention comprehends changes, variations and modifications 65 which come within the scope of the claims hereunto appended.

Fig. I is a front elevation of a furnace made in accordance with my invention, part 70 of the casing of said furnace being broken away to show the interior of said furnace.

Fig. II is an enlarged fragmentary vertical section showing the manner in which the air space is arranged and also showing the baffle member associated with the fur- 75 nace.

Fig. III is a cross section on the line III-III of Fig. I.

Fig. IV is an enlarged cross section showing the manner of connecting together the 80 ends of the outer wall and the inner lining member of the furnace.

In the drawing, A designates a furnace made in accordance with my invention, said furnace comprising the usual combustion heater B, which is provided with the usual appurtenances, such as a fuel door, an ash door and draft-regulating devices, which need not be described herein. Arranged around the lower portion of the combustion 85 heater B is a base section 1, which is in the form of an annular sheet of metal extending upwardly from the floor, said base section being provided with an annular bead 2 which performs the double function of 90 strengthening said section and acting as a stop for the section of the furnace casing 95 which is arranged above said base section.

Located above the base section 1 is an intermediate casing section 3. The intermediate casing section 3 comprises a sheet of metal which is shaped so that it is circular in cross section and the ends of said sheet of metal are joined together to produce an annular wall. To permit the ends of the intermediate casing section 3 to be drawn together to provide a reasonably tight joint, I provide one of said ends with an outwardly extending vertical flange 4 (Fig. IV), which flange is formed by bending a portion of the metal of said casing member outwardly and then doubling said 100 105 110

metal backwardly on said outwardly extending portion to provide a 2-ply vertical flange. The extreme end 5 of the intermediate casing member is bent approximately at 5 a right angle to the vertical flange 4, and said portion 5 is approximately in alignment with the main wall of the circular casing member. The opposite end of the intermediate casing section is provided with a 10 single ply outwardly extending flange 6 which is formed by merely bending the extreme end portion of said annular sheet of metal outwardly, as shown in Fig. IV. In arranging the intermediate casing member 3 above the base member 1, said intermediate section is so located that the lower portion thereof surrounds that portion of the base section which is 15 above the annular bead 2. The ends of the intermediate section are then drawn together and bolts 7 are passed through the 2-ply flange 4 and the single ply flange 6 to securely fasten the opposite ends of the intermediate section together. When the 20 end portions of the intermediate section 3 are drawn together as described, it is apparent that a very tight joint will be obtained because of the fact that there is very close contact between the comparatively 25 wide portion 5 and the adjacent portion of the member 3 and between the flanges 4 and 6.

Located above the intermediate casing member 3 is the bonnet 8 of the furnace, said bonnet 8 being of the usual construction and being provided with a lower portion which is surrounded by the upper portion of the intermediate casing member 3. It is plain from the foregoing that the 30 elements of the furnace which compose the outer casing thereof are very securely connected together, the lower and upper portions of the intermediate member 3 surrounding the upper portion of the base member 1 and the lower portion of the bonnet 8, respectively, and the ends of said intermediate member 3 being drawn tightly together to cause said base member and said bonnet to be tightly gripped by said intermediate section.

Located adjacent to the lower portion of the bonnet 8 is a ring 9. The ring 9 is arranged concentric with the circumferential wall of the bonnet 8, and said ring is of such 55 diameter that an annular space is provided between said ring and the inner face of said circumferential wall of the bonnet. To support the ring 9 I employ a plurality of brackets 10 which are preferably approximately Z-shaped and are riveted or otherwise secured to the wall of the bonnet 8, and to said ring 9, as shown in Figs. I and III. Located adjacent to the upper end of 60 the base member 1 is a second ring 11 which, like the ring 9, is spaced apart from the

outer wall of the furnace, said ring 11 being in vertical alignment with the ring 9. The ring 11 is secured to the upper portion of the base member 1 by means of substantially Z-shaped brackets 12 similar to the brackets 70 10 which support the ring 9.

Supported by the rings 9 and 11 is an inner lining member 13. The inner lining member 13 is an exact counterpart of the intermediate casing member 3, except that said inner lining member is smaller in diameter. The inner lining member, like the intermediate casing member, is shaped to form a circle in cross section, and the end portions of said inner lining member are provided with a 2-ply flange 14 and a single ply flange 15, which are adapted to be drawn together by bolts 16 to provide a tight joint, as shown in Fig. IV. The 2-ply flange 14 is also provided with a portion 17 which is similar 80 to and functions like the portion 5 of the 2-ply flange 4 on the intermediate casing member 3. As shown clearly in Fig. III, the upper portion of the inner lining member 13 overlaps and surrounds the lower 85 portion of the ring 9, and the lower portion of said inner lining member overlaps and surrounds the upper portion of the ring 11.

It is plain from the foregoing that the rings 9 and 11 are in fixed positions relative to the outer casing wall of the furnace, and it is likewise plain that when the ends of the inner lining member 13 are drawn together so that said inner lining member grips said rings 9 and 11, said inner lining member 13 will also be held in a fixed position relative to the outer wall of the casing, so that an annular air space of uniform width throughout will be provided, which space will remain uniform during the life of the furnace. 95

An important feature in connection with the furnace casing disclosed herein resides in the ease which it may be assembled, it being quite apparent that there is no accurate fitting together of parts as there is in connection with the casings of some furnaces now in use. The intermediate casing member 3 and the inner lining member 13 are expanded when the casing is being assembled, consequently they will very readily 100 slip into place, after which said parts may be drawn together by the bolts 7 and 16 to tightly connect the various parts of the casing together.

I have found by experiment that the 120 volume of heat dissipated through the medium of radiation is greatly reduced by interposing a baffle such as that designated by the reference character 18 between the air space of the furnace casing and the 125 combustion heater B thereof. The baffle 18 is semi-circular in cross-section as shown in Fig. II, and is of such diameter that it is spaced some distance inwardly from the inner lining member 13. As a means for 130

supporting the baffle member 18 I employ a ring 19, which is located within the ring 9 (Figs. I and II), and said ring 19 is supported by the ring 9 through the medium of a plurality of brackets 20. Located at the upper edge of the baffle member 18 is a pair of hook-shaped members 21 which are adapted to engage the ring 19, as shown in Figs. I and III, so as to support the baffle member. As will be seen by referring to Fig. III, the baffle is not supported at its lower end, said baffle merely being suspended from the ring 19.

I claim:

1. A heating furnace comprising a combustion heater, an outer casing, a lining member located within said outer casing and spaced apart therefrom to provide an unobstructed air space which extends entirely around said combustion heater, said lining member comprising a sheet of material having ends capable of being drawn together to reduce the diameter of said lining member, means whereby a comparatively air-tight joint is provided between the cooperating end portions of said lining member, and means whereby said lining member is retained in a fixed position relative to said outer casing of the furnace, said means comprising an annular member arranged at the upper end of said lining member and located entirely within said outer casing.

2. A heating furnace comprising a combustion heater, an outer casing, a lining member located within said outer casing and spaced apart therefrom to provide an unobstructed air space which extends entirely around said combustion heater, said lining member comprising a sheet of material having ends capable of being drawn together to reduce the diameter of said lining member, means whereby a comparatively air-tight joint is provided between the cooperating end portions of said lining member, and means whereby said lining member is retained in a fixed position relative to said outer casing of the furnace, said means comprising annular members arranged at the upper and lower ends of said lining member, said annular members being located entirely within said outer casing and being frictionally gripped by said lining member.

3. A heating furnace comprising a combustion heater, an outer casing, a lining member located within said outer casing and spaced apart therefrom to provide an unobstructed air space which extends entirely around said combustion heater, said lining member comprising a sheet of material bent in circular form and having ends capable

of being drawn together to reduce the diameter of said lining member, overlapping means whereby a comparatively air-tight joint is provided between the cooperating end portions of said lining member, and means whereby said lining member is retained in a fixed position relative to said outer casing of the furnace, said means comprising rings arranged at the upper and lower ends of said lining member and fixed to said outer casing, said rings being located entirely within said outer casing and being frictionally gripped by said lining member.

4. A heating furnace comprising a combustion heater, an outer casing member surrounding said combustion heater, an inner lining member arranged within said outer casing member and spaced apart therefrom to provide an air space, means comprising fixed annular members located above and below said inner lining member whereby same is retained in a fixed position relative to said outer casing member, and a baffle interposed between said inner lining member and said combustion heater.

5. A heating furnace comprising a combustion heater, an outer casing member surrounding said combustion heater, an inner lining member arranged within said outer casing member and spaced apart therefrom to provide an air space, means comprising a pair of fixed rings one of which is located at the upper edge of said inner lining member and the other at the lower edge thereof whereby said inner lining member is retained in a fixed position relative to said outer casing member, and a baffle interposed between said inner lining member and said combustion heater, said baffle being supported by said upper ring.

6. A heating furnace comprising a combustion heater, an outer casing member surrounding said combustion heater, an inner lining member arranged within said outer casing member and spaced apart therefrom to provide an air space, means comprising a pair of fixed rings, one of which is located at the upper edge of said inner lining member and the other at the lower edge thereof whereby said inner lining member is retained in a fixed position relative to said outer casing member, a smaller ring arranged within the aforesaid upper ring and supported thereby, and a baffle suspended from said inner ring, the body of said baffle being interposed between said inner lining member and said combustion heater.

In testimony that I claim the foregoing I hereunto affix my signature.

WILLIAM A. TOOHER.
